J. P. WILLIAMS.
ELECTRIC BURGLAR ALARM SYSTEM.
APPLICATION FILED APR. 27, 1910.

1,115,359.

Patented Oct. 27, 1914.

UNITED STATES PATENT OFFICE.

JOHN P. WILLIAMS, OF NEW YORK, N. Y., ASSIGNOR TO ELECTRIC BANK PROTECTION COMPANY, A CORPORATION OF DELAWARE.

ELECTRIC BURGLAR-ALARM SYSTEM.

1,115,359.

Specification of Letters Patent. Patented Oct. 27, 1914.

Application filed April 27, 1910. Serial No. 558,035.

To all whom it may concern:

Be it known that I, JOHN P. WILLIAMS, a citizen of the United States, and resident of New York, in the county and State of New York, have invented certain new and useful Improvements in Electric Burglar-Alarm Systems, of which the following is a specification.

This invention relates to electric burglar-alarm systems, and it has particular relation to an improved protected alarm structure comprised in such systems.

The object of my invention is to provide a simple and improved burglar-alarm system in which the protected alarm structure will be itself protected either electrically or mechanically or both electrically and mechanically independently of the main protected structure and independently of the circuit connections between the main protected structure and the protected alarm structure.

In the drawings—Figure 1 is a diagrammatic representation of the main parts of a burglar-alarm system embodying my improvements, the protected alarm structure being shown in cross-section. Fig. 2 is a detail plan view illustrating the preferred arrangement of the thermostatic cable element with relation to the casing plates of the protected alarm structure. Fig. 3 is a detail cross-section of one type of thermostatic cable.

Corresponding parts in all the figures are denoted by the same reference characters.

Referring to the drawings, the dotted line 1 indicates the guarded structure or main structure protected by the burglar-alarm system. The 'guarded structure as herein indicated may be the vault, safe, or other structure which it is desired to protect in a bank or other building, or the building or apartment itself or a part thereof. In the type of burglar-alarm systems to which my improvements particularly relate, the main guarded structure 1 is itself electrically protected in a suitable manner so that an attack upon the same or an attempt to gain entrance thereto will sound an alarm, this electrical protection usually comprising batteries and circuits, switches and relays and other devices arranged within the guarded structure, and said circuits are connected by a cable, usually exposed and itself

protected, extending to an alarm structure 55 suitably located and containing the alarm. The alarm structure is indicated at 2, and it usually comprises a suitable casing containing the operative parts of the alarm mechanism. The alarm structure 2 may be 60 located at any desired point where it is desired to sound an alarm by action of the electrical protective means of the main guarded structure 1, but it is usually and preferably placed upon the outside of the 65 bank building or apartment or structure within which is located the guarded structure 1, where it is exposed to view. Heretofore, the alarm structure 2 has been itself electrically protected against an attack upon 70 it or an attempt to gain entrance thereto for the purpose of disabling or destroying the alarm mechanism contained therein, by direct connection with the main circuits carried by the cable extending from the main 75 guarded structure 1 to the alarm structure 2 and operating through the batteries and trips and relays or other circuit-connection devices contained within the main guarded structure 1. The result of the conditions 80 just stated is that, should the cable connection between the guarded structure 1 and alarm structure 2 be disabled or these structures be electrically disconnected in any manner, an attack could then be made upon 85 the alarm structure 2, which is exposed to view and readily accessible, for instance upon the street wall of the building, and the alarm means contained therein could be disabled or destroyed and the system thus 90 rendered inoperative.

My invention comprises improvements whereby the alarm structure 2 is itself effectively protected independent of any circuit connections with the main guarded structure 1 or through the cable extending between the latter and the alarm structure, whereby the alarm structure is operatively protected entirely within itself and without dependency upon any external or supplementary source of electrical connection or current supply. The protected alarm structure 2, in my invention and improvements, thus constitutes in itself an independent and effective burglar-alarm system 100 105 whereby the alarm cannot be disabled without the sounding thereof, in case of an attack upon the alarm structure, whatever

may be the electrical conditions of the main guarded structure 1 or the circuits in the connecting cable extending therefrom.

The protected alarm structure, 2, comprised in my invention, embodies a suitable casing forming an enclosure the main walls of which preferably consist of an outer plate, 3, and an inner plate, 4, separated from each other and insulated, as at 5. 10 Within this structure is arranged the battery or other source of electrical energy for independently protecting the alarm structure, and in the circuit arrangement herein indicated I have shown two batteries in series, as at 6 and 7. The alarm signal is also housed within the structure 2, and is herein shown as consisting of a suitably mounted gong, 8. An electro-magnet device, as at 9, of usual construction, is also mounted within the structure 2 and comprises the usual hammer, 10, for sounding the gong. The foregoing mechanism, in connection with the circuits through the batteries inclosed by the alarm structure, as 15 hereinafter described, will effect the electrical sounding of the alarm. In addition to such electrical mechanism, I also preferably provide within the alarm structure 2 mechanical means, as at 11, for sounding the 20 alarm. Such mechanical means may be of any suitable or adapted construction, for instance an arrangement similar to that shown in the patent to M. F. Juruick No. 1,038,594, granted September 17, 1912, and as herein 25 illustrated said mechanism comprises a spring-motor, 12, adapted to actuate a pivoted hammer, 14, in contact with the gong 8, said spring-motor being normally locked by the engagement of a pivoted lever, as at 30 30 35 40 45 50 55 60 65 70 75 80 85 90 95 100 105 110 115 120 125 130 135 140 145 150 155 160 165 170 175 180 185 190 of the alarm structure 2, while the members 20 and 21 are in contact with the outer casing plate 3 of the structure 2, whereby the insertion of a metallic instrument in contact with either of the members 20 or 21 and the member 22 will cause the sounding of the alarm. It will be understood that the circuit connections of the members 20, 21 and 22 may be arranged in any suitable operative manner, and it will also be noted that an attempt to drill through the casing whereby a metallic instrument is brought into contact with the outer plate 3 and the inner plate 4 will also sound the alarm, such parts being in circuit connection with the battery power within the casing of the structure 2, as hereinafter set forth.

My improvements also comprise means for protecting the alarm structure 2 thermally, so that the application of heat or flame will result in sounding the alarm. In carrying out this feature, I preferably employ a thermostatic cable, 27, suitably arranged, such a cable being shown as extending over the outer face of the perforated plate 22 and in the space between the inner and outer plates 3 and 4 of the alarm structure casing, the cable being arranged so that it extends continuously with relation to the surface area of the plates, as indicated in Fig. 2. The thermostatic cable may be of any suitable or adapted construction, but I have herein shown a construction in which it consists of a central wire, 28, surrounded and inclosed by a fusing element, 29, around which is provided an insulation, 30, over which is wound a wire, 31, inclosed within an outer insulation, 32, whereby the application of a sufficient degree of heat or flame to cause the fusing of the element 29 and the melting of the insulation 30 will short circuit the wires 28 and 31 and cause the sounding of the alarm. The wires 28 and 31 are connected to opposite sides of the battery power contained within the alarm structure 2, by wires, as at 33 and 34, or by connection with the casing plates 3 and 4, or in any other suitable operative manner. The thermostatic construction and arrangement as herein shown is such that an attack upon the protected alarm structure 2 by the application of heat or flame at practically any point of its casing body will cause the sounding of the alarm.

The front portion of the protected alarm structure 2 may be mounted and secured in any suitable manner, and preferably comprises a face-plate, 35, to which the members 20, 21 and 22 are connected and which is adapted to normally contact with the outer casing plate 3, while the members 20 and 21 are in electrical connection with said face-plate 35. But in the evident securing means of said front portion of the alarm structure 2 is preferably comprised a screw, 130

as at 36, the head of which is exposed exteriorly of the alarm structure 2 and the stem of which is in operative connection with the lever 15 controlling the mechanical device for operating the hammer 14. This connection is normally maintained by a notched end, 37, upon the stem of the screw, engaging a supplementary lever, 38, pivotally carried upon an arm, 39, extending from the fulcrum, 40, of the lever 15, said supplementary lever 38 being maintained in engagement with the notched end 37 by a spring, as at 41. Thus, in the normal operation of the lever 15 and mechanical device 11, by action of the armature 19, the connection between the screw 36 and the lever 15 is maintained, but should an attempt be made to withdraw the screw 36 in an attack upon the protected alarm structure 2, the outward movement of the screw will trip the lever 15 and release the mechanical device 11 and result in the sounding of the alarm by operation of the hammer 14.

The front portion of the protected alarm structure 2, is movably mounted with relation to the casing of the structure. For instance, it may be constituted by a hinged door comprising the members 20, 21 and 22, and in the general arrangement for securing such movable part in position I may employ screws, as at 42, passing through the face-plate 35 into engagement with an extension of the outer casing plate 3. To provide for sounding the alarm when said front portion is moved away from the casing of the structure 2, the face-plate 35 preferably carries at its inner face lugs, 24, the inner ends of which normally maintain spring contacts, 26, away from the inner casing plate 4, said spring contacts being in connection with the outer casing plate 3, whereby when the lugs 24 move outwardly from the spring contacts 26, the latter are released and contact with the inner casing plate 4, thus completing the circuit and causing the sounding of the alarm.

In general, the circuit arrangements of the devices comprised in the protected alarm structure 2, with the battery source of electrical energy also contained in said structure, may be of any suitable or adapted construction whereby the mechanical device will be released and the alarm sounded by action of the mechanical hammer 14 or the electro-magnet 9 will be energized to cause the action of the electrically-operated hammer 10. I have herein shown a circuit arrangement in which, when the alarm housing is tampered with and the plates 3 and 4 therefore brought into electrical connection, the following circuit through an automatic drop, 45, is established: from the positive side of the battery 6, through a wire, 46, plate 3, plate 4, a wire, 60, and the coils of the drop 45, the frame of the drop, a wire, 54, and a

wire, 47, to the negative side of the battery 6. This actuates the drop 45 and the circuit through the electric alarm 9 is established as follows: from bell 9, through a wire 43, plate 3, wire 46, battery 6, wire 70 47, wire 60, the frame of the drop 45, and then through a wire 44 to the electric alarm 9. The wire 48 is also extended to the armature of a relay, 49, contained within the protected alarm structure 2, and from 75 the contact of said relay a wire, 50, extends through the battery 7 to the wire 46. In the circuit connections with the battery, the wire 47 is extended to the frame of the automatic drop 45, as at 54. With 80 the foregoing arrangement of circuits and operative parts included therein, an attack upon the protected alarm structure 2 under any of the conditions hereinbefore described, will result in the sounding of the 85 alarm. I preferably also employ a trip wire, as at 51, extending from a normally-open contact, as at 52, one side of which is carried upon the arm of the pivoted lever 15 which carries the armature 19 of the 90 electro-magnet 18, and this trip wire 51 extends to a connection with the inner casing plate, as at 53. The operative office of the trip wire arrangement is substantially the same as that of the similar arrangement 95 shown and described in the Juruick patent hereinbefore referred to, whereby the action of the mechanical device for sounding the alarm will cause the action of the electrical device for sounding the alarm.

From the foregoing description, it will be understood that the protected alarm structure 2 is adapted for independent operation in itself and by means of its own battery power or source of electrical energy, upon 100 any conditions of attack upon or an attempt to gain entrance to the alarm structure, without reference to or dependency upon any electrical action of the protective means of the main guarded structure 1 or circuit 105 connections therewith through the cable connecting the guarded structure 1 and the protected alarm structure 2. But the usual electrical connections are provided between the main guarded structure 1 and the alarm 110 structure 2, whereby an attack upon the guarded structure 1 or upon the connecting cable will sound the alarm within the protected alarm structure 2. The circuit connections between the main guarded structure 1 and the protected alarm structure 2 are substantially the same as those shown in the Juruick patent hereinbefore referred to, including closed circuit connections with the mechanical device 11 and open circuit connections 115 with the electrical device 9, whereby the opening of the closed circuit will cause the operation of the mechanical device and the closing of the open circuit will cause the operation of the electrical device, and 120 125 128

reference may be had to said patent for a more detail explanation of the arrangement and operation of such circuits. I have herein shown the cable connection between 5 the main guarded structure 1 and the protected alarm structure 2 as including closed circuit wires, 55 and 56, extending from the relay 49, which are employed to protect the connecting cable against cutting and are not 10 dependently employed for the protection of the alarm structure 2, and open circuit wires, 57 and 58, extending from the electro-magnet 9 of the electrically-operated hammer 10, which operate to cause the sounding 15 of the alarm when their circuit is closed by action of the protective devices comprised in the main guarded structure 1. The cable connection also includes an extension of the trip wire 51, whereby the operation of the 20 mechanical device through the cable connections will cause the operation of the electrical means for sounding the alarm and said electrical means will operate continuously until its circuit is again opened. In 25 the arrangement for effecting this operation, the extension of the trip wire 51 is carried to the coil of an automatic drop, 61, within the guarded structure 1, and from thence to a normally-closed contact, 62, of said 30 automatic drop. The normally-closed circuit constituted by the wires 55 and 56 has its battery within the guarded structure 1, as at 63. The wires 57 and 58 of the normally-open circuit are extended respectively 35 as follows: the wire 57 through a battery, 64, within the guarded structure 1, to the frame of said automatic drop 61, and the wire 58 to a normally-open contact, 65, the 40 operation of which is governed by the action of said automatic drop 61.

It will be understood that the arrangement and operation of the normally-closed circuit 55-56 and the normally-open circuit 57-58 and the trip wire 51, with their 45 sources of electrical energy and the automatic drop 61 arranged within the main guarded structure 1, is substantially the same as is shown in the before-mentioned Jurick patent, and that these wires are extended in a cable leading to the protected alarm structure 2 in substantially the same manner as shown in said patent, to govern the operation of the mechanical and electrical alarm means within the protected 50 alarm structure 2 in case of an attack at the guarded structure 1. But the extension of the electrical protective system of the main guarded structure 1 to the protected alarm structure 2, in the general burglar-alarm 55 system to which my present improvements are adapted and as illustrated in said before-mentioned Jurick patent, is not essential to the operation of the alarm mechanism within the protected alarm structure 2 in 60 case of an attack only upon said alarm

structure, it being understood that in my present improvements the alarm structure 2 is fully protected in itself without dependence upon any circuit connections with the main guarded structure 1, said alarm 70 structure 2 having its own independent protective circuits and sources of electrical energy therefor entirely within itself and in connection with the inclosed alarm mechanism, whereby it is adapted for independent 75 operation by means of its own circuits and sources of electrical energy when any attempt is made to gain entrance thereto.

With reference to the circuits through the circuit connections with the main guarded 80 structure 1, including the trip wire 51, it will be noted that when the normally-closed circuit 55-56 is opened by an attack thereon and the armature of the relay 49 is thus released, the circuit is completed as follows: 85 from one side of batteries 6 and 7 through wire 50, the armature of the relay 49, the wire 48, the coils of the electro-magnet 18, and wire 47, to the opposite side of the batteries. A multiple circuit is also then completed 90 across the automatic drop 45 by the action of the relay 49 in establishing the circuit just stated, as follows: from one side of battery 6 through wire 47, the wire 54, the frame of the automatic drop 45, the wire 95 60 through the coils of said drop to the inner casing plate 4, the wire 48 from said inner casing plate, the armature of the relay 49, and the wire 50 through battery 7 to the other side of battery 6. When the electro-magnet 18 is thus energized, the mechanically-operating alarm mechanism will be started in 100 operation by the action of the armature 19 of said electro-magnet, which carries the release lever 15, and the open trip circuit 105 including the wire 51 is then closed and completed as follows: The action of the armature 19 closes the open contact 52 and establishes the following circuit traced from wire 51, through the coil of the automatic 110 drop 61 in the guarded structure 1, the normally-closed contact 62, the frame of the drop 61 and the wire 57 to the negative side of the battery 64 in the guarded structure 1, through the battery wire 57, wire 43, the outer 115 casing plate 3, rod 36, contacts 52 and back to wire 51. This complete trip circuit operates through battery 64 and thus energizes the automatic drop 61 and causes the same to operate to close the normally-open 120 contact 65 thereof, and the electrically-operated alarm mechanism 9 is then actuated through the circuit completed as follows: from the positive side of the battery 64, through the wire 57, the coils of the 125 alarm mechanism 9, the wire 58, to the closed contact 65, the frame of the automatic drop 61, and the extension of the wire 57 therefrom, to the other or negative side of the battery 64.

It will be noted that the automatic drop 45 is energized to throw the wire 44 in circuit simultaneously with the energizing of the electro-magnet 18, and a multiple ringing circuit is completed through the electrically-operated alarm mechanism 9 and the battery 6 as follows: from the negative side of the battery 6, through the wire 47, the wire 54, the frame of the drop 45, the wire 44 (the contact for which is then closed at the drop 45), the coils of the alarm mechanism 9, the wire 43, the outer casing plate 3 of the protected alarm structure 2, and the wire 46, to the opposite side of the battery 6.

If desired, the connecting cable extending 15 between the guarded structure 1 and the protected alarm structure 2 may contain circuit wires suitably arranged in any adapted manner and in connection with any 20 adapted devices, for testing the batteries contained in the protected alarm structure or for indicating the action and service 25 status of these batteries at any time without occasion for entering the protected alarm structure itself.

The general operation and advantages of my invention and improvements will be readily understood by those skilled in the art to which they appertain. The features 30 of the improvements provide a protected alarm structure which constitutes in itself an independent and effective burglar-alarm system whereby the alarm cannot be disabled without the sounding thereof, and which, in its connection with a general burglar-alarm 35 system embodying a main guarded structure and a main protective circuit or circuits extending to the alarm structure, is effectively protected independent of the main 40 protective circuit or circuits. The general features of improvement as comprised in my invention also have a wide range of application to various different types of alarm systems, whatever may be the particular 45 structural characteristics of the main system itself, as will be readily understood.

I do not desire to be understood as limiting myself to the detail construction and arrangement of parts or circuits as herein 50 shown and described, as it is manifest that variations and modifications therein may be resorted to, in the adaptation of my invention to varying conditions of use, without departing from the spirit and scope of my 55 invention and improvements. I therefore reserve the right to all such variations and modifications as properly fall within the scope of my invention and the terms of the following claims.

Having thus described my invention, I 60 claim and desire to secure by Letters Patent:

1. In a burglar-alarm system, a structure to be guarded, an alarm housing, an alarm 65 mechanism arranged within said housing,

an electrical protective system comprising a main protective circuit extending between said structure to be guarded and said alarm mechanism, and a supplementary electrical protective system entirely comprised within 70 said alarm housing and constituting a protective system without dependence upon said main protective system, said supplementary system being operatively independent of said circuit connections between said structure to be guarded and said alarm mechanism, whereby the alarm housing is in itself entirely protected without any dependency upon any part of the main protective system external thereof.

2. In a burglar-alarm system, a structure to be guarded, an alarm housing, an alarm mechanism arranged within said housing, an electrical protective system comprising a main protective circuit extending between 80 said structure to be guarded and said alarm mechanism, said alarm mechanism comprising mechanically-operating means contained within said alarm housing for actuating the alarm, and a circuit protecting said alarm housing and having its source of energy arranged therein and actuating said mechanically-operating means, said circuit for said housing being supplementary to the electrical protection of said structure to be guarded 90 and constituting a protective system without dependence upon said external main protective circuit and operatively independent of any other part of the system, whereby the alarm housing is in itself protected through 100 said mechanically-operating means without dependency upon any part of the main protective system.

3. In a burglar-alarm system, a structure to be guarded, an alarm housing, an alarm mechanism arranged within said housing, an electrical protective system comprising a main protective circuit extending between 105 said structure to be guarded and said alarm mechanism, said alarm mechanism comprising mechanically-operating and electrically-operating means contained within said alarm housing for actuating the alarm, and a circuit protecting said alarm housing and having its source of energy arranged therein and actuating said mechanically-operating and electrically-operating means, said circuit for said housing being supplementary to the electrical protection 110 of said structure to be guarded and constituting a protective system without dependence upon said external main protective circuit and operatively independent of any other part of the system, whereby the alarm housing is in itself entirely protected 115 through said mechanically-operating and electrically-operating means without dependency upon any part of the main protective system.

4. In a burglar-alarm system, a structure 120

- to be guarded, an alarm housing, an alarm mechanism arranged within said housing, an electrical protective system in connection with said alarm mechanism for protecting 5 the structure to be guarded, and a supplemental electrical protective system in connection with said alarm mechanism for independently protecting said alarm housing, said supplemental system constituting a 10 protective system without dependence upon said main protective system and operatively independent of any circuit connections with the structure to be guarded, whereby the alarm housing is in itself entirely protected 15 without dependency upon any part of the main protective system external thereof.
5. In a burglar-alarm system, an electrically-protected structure to be guarded, an alarm mechanism in connection with the 20 electrical protection for said structure to be guarded, and a housing for said alarm mechanism electrically protected in connection with said alarm mechanism, the electrical protection of the alarm housing constituting a protective system without dependence upon the electrical protection of the structure to be guarded and operatively independent of any other part of the system, whereby the alarm housing is in itself 25 entirely protected without dependency upon any part of the main protective system external thereof.
6. In a burglar-alarm system, an electrically-protected structure to be guarded, an alarm mechanism in connection with the 30 electrical protection for said structure to be guarded, a housing for said alarm mechanism, and a supplementary electrical protective system completely arranged within 35 said alarm housing and in connection with the alarm mechanism therein and constituting a protective system without dependence upon the electrical protection of the structure to be guarded and operatively 40 independent of any other part of the system, whereby the alarm housing is in itself entirely protected without dependency upon any part of the main protective system external thereof.
- 45 7. In a burglar-alarm system, a structure to be guarded, an alarm mechanism exterior of said structure to be guarded, a main electrical protective system having its source of energy arranged within said 50 structure to be guarded and extending therefrom to said alarm mechanism, a housing for said alarm mechanism, and a supplementary electrical protective system having its source of energy arranged within said 55 alarm housing and in connection with the alarm mechanism therein and constituting a protective system without dependence upon the electrical protection of the structure to be guarded and operatively independent of any other part of the system, whereby the alarm housing is in itself 60 entirely protected without dependency upon any part of the main protective system external thereof.
- 65 8. In a burglar-alarm system, a structure to be guarded, an alarm mechanism exterior of said structure to be guarded, a housing for said alarm mechanism, means for electrically protecting said structure to be guarded in connection with said alarm mechanism, and supplementary means for electrically protecting said alarm housing in connection with said alarm mechanism, said supplementary means constituting a protective system without dependence upon the electrical protection of the structure to be guarded and operatively independent of any other part of the system, whereby the alarm housing is in itself entirely protected without dependency upon any part of the main protective system external thereof.
- 70 9. In a burglar-alarm system, a structure to be guarded, an alarm mechanism exterior of said structure to be guarded, means for electrically protecting said structure to be 75 guarded in connection with said alarm mechanism, and a housing for said alarm mechanism comprising in itself a complete electrical protective system for actuating said alarm mechanism when an attack is 80 made upon said alarm housing, said electrical protective system for said housing being supplementary to the electrical protection of said structure to be guarded and constituting a protective system without dependence upon said main electrical protection and operatively independent of any other part of the system, whereby the alarm housing is in itself entirely protected without dependency upon any part of the main protective system external thereof.
- 85 10. In a burglar-alarm system, an alarm mechanism, a housing therefor, said alarm mechanism comprising mechanically-operating and electrically-operating means for actuating the alarm, means for locking said mechanically-operating means against operation, and an electric protective circuit comprised within said alarm housing and in operative connection with said locking 90 means to release the same, said protective circuit being also in connection with said electrically-operating means and having its source of energy arranged within said alarm housing, whereby said alarm housing 95 is electrically protected for the actuation of either or both of said mechanically-operating and electrically-operating means independent of any external agency.
- 100 11. In a burglar-alarm system, an alarm mechanism, a housing therefor, said alarm mechanism comprising mechanically-operating and electrically-operating means for actuating the alarm, means for locking said mechanically-operating means against operation 105
- 110
- 115
- 120

eration, an electric protective circuit comprised within said alarm housing and in operative connection with said locking means to release the same, said protective circuit being also in connection with said electrically-operating means and having its source of energy arranged within said alarm housing, and supplementary mechanical means exposed exteriorly of the housing for controlling said locking means independently of the action of said electric circuit, whereby said alarm housing is electrically protected for the actuation of either or both of said mechanically-operating and electrically-operating means independent of any external agency and protected by said supplemental mechanical means independent of the electrical protection.

12. In a burglar-alarm system, an alarm mechanism, a housing therefor, thermostatic means comprised in said housing and embodying electrical conductors in connection with the alarm mechanism, and a source of electrical energy arranged within said alarm housing and in connection with said conductors, whereby said alarm housing is electrically protected against the action of heat or flame independent of any external agency.

13. In a burglar-alarm system, an alarm mechanism, a housing therefor, said alarm mechanism comprising mechanically-operating means arranged within said alarm housing, means for locking said mechanically-operating means against operation, an electrical circuit comprised within said housing and controlling said locking means, and a supplementary mechanical member in trip connection with said locking means and exposed exteriorly of said alarm housing, whereby an attack causing movement of said mechanical member will trip said mechanically-operating means and cause the actuation of the alarm independent of the action of said electric circuit.

14. In a burglar-alarm system, an alarm mechanism, a housing therefor, said alarm mechanism comprising mechanically-operating means arranged within said alarm housing, means for locking said mechanically-operating means against operation, an electrical circuit comprised within said housing and controlling said locking means, and a screw in trip connection with said mechanically-operating means and exposed exteriorly of said alarm housing, whereby an attack causing movement of said screw will trip said mechanically-operating means and cause the actuation of the alarm independent of the action of said electric circuit.

15. In a burglar-alarm system, an alarm mechanism, a housing therefor, said alarm mechanism comprising mechanically-operating means arranged within said alarm housing, means for locking said mechanically-

operating means against operation, said locking means having a trip lever, and a screw the inner end of which is in trip engagement with said trip lever and the head of which is exposed exteriorly of said housing, whereby an attack causing movement of said screw will trip said lever or release the mechanically-operating means and cause the actuation of the alarm.

16. In a burglar-alarm system, an alarm mechanism, a housing therefor, said alarm mechanism comprising mechanically-operating means arranged within said alarm housing, an electric circuit comprised within said housing and controlling the operation of said mechanically-operating means, and a mechanical member in trip connection with said mechanically-operating means and exposed exteriorly of said housing, whereby said mechanically-operating means will be released either electrically through said circuit or by movement of said mechanical member to actuate the alarm.

17. In a burglar-alarm system, an alarm mechanism, a housing therefor, said alarm mechanism comprising mechanically-operating means arranged within said alarm housing, an electric circuit comprised within said housing and controlling the operation of said mechanically-operating means, and a mechanical member in flexible trip connection with said mechanically-operating means and exposed exteriorly of said alarm housing, whereby said mechanically-operating means will be released either electrically through said circuit or by movement of said mechanical member to actuate the alarm and the operation of said electrical circuit will not affect the normal operative status of said mechanical flexible trip means.

18. In a burglar-alarm system, an alarm mechanism, a housing therefor, an electrical circuit protecting said housing and controlling said alarm mechanism, and mechanical means exposed exteriorly of said alarm housing and interiorly thereof in mechanical trip connection with said alarm mechanism to cause the actuation of the alarm mechanism by movement of said mechanical means, whereby said alarm housing is mechanically-protected against attack by movement of said mechanical means independent of the action of said electric circuit.

19. In a burglar-alarm system, an alarm mechanism, a housing inclosing the alarm and all the elements of said alarm mechanism, mechanical means operatively comprised in said alarm mechanism for actuating the alarm, means for locking said mechanically-operating means against operation, and electrical means operatively comprised in said alarm mechanism for actuating the alarm, and an electric protective system inclosed within said housing and in circuit

connection therewith and in operative connection with said locking means to release the same and with said electrical means to actuate the same, whereby an attack upon 5 said alarm housing exteriorly will cause the operation of either of said mechanically-operating and electrically-operating means and the alarm housing is both mechanically and electrically protected in itself independent 10 of any external agency.

20. In a burglar-alarm system, a structure to be guarded, an alarm housing, an alarm mechanism arranged within said housing, mechanically-operating means arranged 15 within said housing and operating to actuate the alarm, means for locking said mechanically-operating means against operation, electrically-operating means arranged within said housing and operating to actuate the 20 alarm, an electrical protective system comprising a main protective circuit extending between said structure to be guarded and said locking means and electrically-operating means within the alarm housing and 25 governing the operation thereof, and a supplementary electrical protective system having its source of energy arranged within said alarm housing and in connection with said mechanically-operating and electrically-op-

erating means and governing the operation 30 thereof independently of any operation through said main protective circuit.

21. In a burglar-alarm system, a structure to be guarded, an alarm housing, an alarm mechanism arranged within said housing, an 35 electrical protective system extending between said structure to be guarded and said alarm mechanism, mechanically-operating means contained within said alarm housing for actuating the alarm, means for locking 40 said mechanically-operating means against operation, said locking means being controlled by the electrical protective system, and supplementary mechanical means exposed exteriorly of said alarm housing 45 for actuating said mechanically-operating means independent of any operation of said electrical protective system extending from said structure to be guarded, whereby said alarm housing is mechanically independently 50 protected.

In testimony whereof I have signed my name in the presence of the subscribing witnesses.

JOHN P. WILLIAMS.
